UNITED STATES PATENT OFFICE.

THOMAS E. MEAGHER, OF PHILADELPHIA, PENNSYLVANIA.

DESIGN FOR A RUG.

SPECIFICATION forming part of Design No. 19,051, dated April 16, 1889.

Application filed March 21, 1889. Serial No. 304,173. Term of patent 3½ years.

To all whom it may concern:

Be it known that I, THOMAS E. MEAGHER, a citizen and resident of the city of Philadelphia, State of Pennsylvania, have invented or 5 produced a new and original Design for a Pattern to be Inwrought into Wilton Rugs and other Carpeting; and I do hereby declare that the photographic illustration accompanying this specification gives and conveys to any 10 one skilled in the art of carpet-weaving a defined and thorough description of the nature of my invention, that is sufficient to enable any one so skilled to use my invention.

What I claim as my invention, and desire to secure by Letters Patent, is—

The design for Wilton rugs, as shown in the photographic illustration accompanying this specification. 15

THOMAS E. MEAGHER.
